UNITED STATES PATENT OFFICE

LOUIS DE VOS, OF SEATTLE, WASHINGTON, ASSIGNOR TO BERRY BUILDING BLOCKS, INC., OF SEATTLE, WASHINGTON, A CORPORATION OF WASHINGTON

DESIGN FOR A WALK AND DRIVEWAY LANTERN

Application filed May 4, 1931. Serial No. 39,704. Term of patent 3½ years.

To all whom it may concern:

Be it known that I, LOUIS DE VOS, a citizen of the United States, residing at Seattle, in the county of King and State of Washington, have invented a new, original, and ornamental Design for Walk and Driveway Lanterns, of which the following is a specification, reference being had to the accompanying drawings, forming a part thereof.

Figure 1 is a perspective view of my lantern.

Figure 2 is a side elevation of my lantern.

I claim—

The ornamental design for a walk and driveway lantern, as shown.

LOUIS DE VOS.
